Specification of Letters Patent. Patented Aug. 16, 1921.

Application filed December 9, 1919. Serial No. 343,505.

To all whom it may concern:

Be it known that I, HARRY E. TIDMARSH, a citizen of the United States, residing at Bangor, in the county of Penobscot, State 5 of Maine, have invented certain new and useful Improvements in Pulp or Paper Machines; and I do hereby declare the following to be a full, clear, and exact description of the invention, such as will enable others 10 skilled in the art to which it appertains to make and use the same.

This invention relates to improvements in the manufacture of paper and pulp, and more particularly to improvements in wet 15 machines for converting pulp into webs and sheets and for removing therefrom the greater portion of its contained moisture.

In the manufacture of paper pulp into webs and sheets, the first problem, after the 20 web has been formed, is to eliminate the water. In the manufacture of paper this is accomplished in two distinct stages. In the first the water is squeezed out; in the second it is driven out by heat. In the manufacture 25 of pulp where the final product is a sheet one quarter of an inch or more in thickness the use of heat is impracticable and reliance must be placed on pressure alone. The more water removed the greater 30 the percentage of actual pulp in the marketed product, which means a saving in transportation charges per unit of dry pulp and a reduction in the freight charges paid for the transportation of water. Clearly then, 35 the more water pressed from the web the better.

The common practice is to pass the newly formed web between pressure rolls, but because of its tenuity it must be supported 40 upon felts during this squeezing operation. As the pressure exerted by succeeding pairs of rolls increases, a point is reached where the wear and tear on the felts becomes prohibitive. This marks the limit of pressure, 45 and the water content of the marketed pulp is thus practically determined by the compression which the felts can successfully withstand.

If the pressure injures the felts, then 50 why not eliminate the felts, increase the pressure, and thus remove a greater quantity of water. This is obviously impossible when the web is first formed for it is then mostly all water and must be supported as 55 it passes between the pressure rolls. But

this objection does not hold with the same force for the later rolls for at this point the strength of the web has increased, and theoretically there seems no good reason why the web should not be passed between 60 the bare rolls. It happens then, that the pulp is best able to pass unsupported through the very rolls which exert the greatest pressure and do most damage to the felts—a happy circumstance. Theoretically 65 there seems no good reason why bare rolls should not be used for the final pressure; actually it happens that the rolls, slippery from the water squeezed from the pulp cannot grip the oncoming web with a 70 grip sufficient to pull it through, and the crushing strength of the pulp itself is too puny to transmit any push from the felts which it has quit. Consequently the web slips and crushes, piling up in the nip of 75 the rolls and passing through in disordered unconnected patches. This is especially true where the pulp passes through the final rolls in the form of separate sheets, each one of which must be individually gripped 80 by the rolls.

Another problem confronting the manufacturer of pulp is the one of dividing the web into sheets of a size convenient for storage or transportation. It has heretofore 85 been proposed to construct machines for the manufacture of sheets of paper and pulp, by forming the web with weakened transverse portions, and subsequently breaking the web into sheets along the weakened 90 portions thus formed, by subjecting the web to a sufficient pull or tension, but in such machines there have been provided two sets of felts and rolls, one set for carrying the web while it is being formed and subjected to 95 pressure, and the other for carrying the web while it is being subjected to its breaking operation.

According to the present invention, the independent rolls for breaking the web into 100 sheets and the second series or set of felts for carrying the web while it is being broken are eliminated; and the present invention provides an improved wet machine for forming the pulp into webs having weakened 105 portions formed therein, and for removing from the web thus formed the greater portion of its moisture, so that the web is obtained in a relatively dry state, and, incident to such operations, for break- 110

ing the web into sheets along the weakened portions thereof.

In the improved wet machine of the present invention the pulp is formed into a sheet or web upon a screen cylinder operating in much the usual manner, but provided with improved means, hereinafter more fully described, for forming weakened portions in the web both transversely and longitudinally. The web thus formed is conveyed by a felt between wringer rolls and thence between two sets of press rolls, between each set of which the web is subjected to a heavy pressure and converted into a relatively dry condition adapted directly for storage and transportation. The first set of press rolls has both the felt and the web passing therethrough, so that the web is subjected to compression, with accompanying removal of water therefrom, while in contact with the felt. The second set of press rolls, however, does not have the felt passing therethrough, but this set acts directly upon the web and effects a further removal of water therefrom. Incident to this compression of the pulp between the second set of press rolls, the web is subjected to a sufficient longitudinal pull or tension to break it along the transverse weakened portions, so that the web is converted into a series of sheets. The second set of press rolls is so constructed that the pulp web will be positively drawn therebetween, as more fully hereinafter set forth. Beyond the final press rolls are situated a pair of diverging off-bearing belts which exert a sufficient transverse pull on every sheet fed from the rolls to break them along the longitudinal weakened portions.

The present invention also includes improvements in the cylinder mold or screen cylinder which rotates in the pulp vat and upon which the web is formed. This cylinder is wound with wire and covered with screen fabric in much the usual way, but it is provided in its peripheral framework, upon which the wire and screens are supported, with rods of relatively large cross section spaced apart a circumferential distance equal to the length of the sheets into which the web is to be broken. These rods are considerably larger than the relatively small rods forming the main circumferential framework of the cylinder and, by reason of their relatively large cross section, they cause the web formed upon the cylinder to be weakened along the lines where these rods occur, for the reason that the pulp does not build up so rapidly upon the portions of the cylinder outside of these rods. The other details of construction of the improved screen cylinder will be more fully hereinafter set forth in connection with the more detailed description of the invention.

The present invention further includes improvements in the construction of the press rolls themselves; in the delivery mechanism for removing the separated sheets; in doctors; and in other features of construction; all as more fully hereinafter set forth and as claimed.

The invention will be further described in connection with the accompanying drawings which illustrate the preferred embodiments thereof and in which—

Figures 1 and 2 together constitute an elevation with parts in section of a wet machine constructed in accordance with the present invention;

Fig. 3 is a view illustrating a modification;

Fig. 4 shows a modified construction of that part of the machine illustrated in Fig. 2;

Fig. 5 is an enlarged top view of part of the delivery mechanism;

Fig. 6 is an enlarged view showing the construction of a preferred embodiment of the second set of press rolls; and

Figs. 7, 8 and 9 are fragmentary views showing the construction of the screen cylinder.

Referring to the drawings, 7 indicates the pulp vat within which the screen cylinder 8 is mounted. The pulp within the vat is maintained at the desired level, in a manner which will be readily understood without illustration, so that the screen cylinder will be immersed therein to the desired extent. The water passing into the interior of the cylinder is withdrawn therefrom through one or both of the ends thereof in a manner well understood and therefore not herein illustrated and described. As the cylinder rotates a layer of pulp is formed thereon, as indicated at 10 in Fig. 1, the thickness of the layer being regulated by the difference in level between the pulp and the water within the cylinder. Arranged above the cylinder is the couch roll 11, carried by a pivotally supported part of the frame and arranged to bear upon the screen cylinder. The layer of pulp formed upon the cylinder is brought into contact with the felt 9 as the cylinder rotates and is removed from the cylinder by the felt which carries it around the couch roll 11 and thence between the sets of rolls referred to below.

The felt and web after leaving the couch roll 11 pass over the guide roll 12 and thence between the three sets of rolls of which the bottom rolls are indicated at 14, 15 and 16 and the top rolls at 29, 30, 31. A second felt passes around the rolls 29, 30 and 31 and around the roller 32 which is adjustable by means of the rods 33, having operating handles 34. The web is accordingly in contact with both the lower felt 9, and the upper felt 28 while it is passing between 130

these three sets of rolls. These rolls serve as wringer rolls and guide rolls and remove a portion of the water from the pulp web. From the roll 16 the felt 9 and web pass 5 downwardly to the first set of press rolls 17, 18, between which they are subjected to a heavy pressure, so that a large portion of the water is squeezed out of the pulp web.

Beyond the first set of press rolls the felt 10 and web pass over the guide roll 19 and the felt then returns around the rolls 20, 21, 22, 23 and 24 to the screen cylinder and couch roll 11, while the web is separated from the felt and passes downwardly over the table 15 or guide 41 to the second set of press rolls 42, 43. The guide roll 22 is vertically adjustable to permit of taking up slack in the endless felt 9 and of adjusting its tension. For this purpose the bearings for the roll 20 22 are mounted upon threaded rods 25 which may be turned from one side of the machine by a hand wheel 26 on a shaft connected by bevel gears 27 to the threaded rods 25.

In the modification illustrated in Fig. 3 25 the upper felt 28 is extended beyond the roll 17 so that the web will be compressed between the two felts as it passes between the rolls 17 and 18.

Suitable provision is made for causing the 30 desired pressure to be exerted between the rolls of the different sets, as, for example, that illustrated in the drawings. Thus the upper press roll 17 is carried by supports 35 pivotally mounted upon the side frames 35 of the machine and having rods 36 connected to weighted levers 37. The connection of each support 35 to its rod 36 is through a spring 38, the tension of which can be adjusted by means of a hand wheel 39 operating upon the threaded portion of the rod.

As above described, the web is separated from the felt after passing over the guide roll 19, and slides down over the surface of the table 41 to the second set of press rolls 45 42, 43. This table is mounted in such a position that it serves to support the web and to guide it and it is also preferably inclined at such an angle that the web will readily slide down over it. The lower press roll 43 is 50 mounted in bearings upon the side frames of the machine. The upper press roll 42 is mounted in bearings formed in supports 44 pivotally mounted upon the side frames of the machine and forced down upon the lower 55 roll by rods 46^a connected to weighted levers 45 and having adjustable springs 46.

The rolls 42 and 43, in the embodiment of the invention illustrated in Fig. 6, are corrugated so that they will grip the web, and 60 the separate sheets into which the web is broken, and draw them positively between them. This corrugation, in the embodiment illustrated, takes the form of threads or grooves cut helically in the cylindrical surfaces of the rolls. In order to overcome any

possible tendency of the helical grooves to shift the web to one side of the machine, two sets of symmetrically disposed helical grooves should be employed. Thus, as illustrated, the grooves begin at the centers of the 70 cylinders and extend toward each end. The depth of the groove, as well as its pitch, can be varied, and the width of the groove, as well as the width of the intermediate cylindrical portions of the roll can likewise be 75 varied. These cylindrical portions are shown as of slightly less diameter than the end portions 42^a and 43^a of the roll, so that, when the sheet or web of pulp is not passing between the rolls, they will bear upon each 80 other only at their ends, but so that, when the pulp is passing between the rolls, they will be forced apart and will then bear only upon the pulp layer. That is, the distance between the grooved portions of the roll is 85 less than the thickness of the pulp web which passes between them so that when the pulp layer is between them, the rolls will no longer bear upon each other at their ends but will exert the desired pressure upon the web 90 to bring about the further removal of water, and resulting drying. The arrangement of the grooves so that they extend from the centers to the ends of the rolls has the further advantage of assisting in causing the 95 water squeezed from the web to travel toward the ends of the rolls so that it is more effectively removed.

It will accordingly be seen that there are provided two sets of press rolls which act 100 successively upon the pulp web and coöperate in the removal of water therefrom, so that the pulp is obtained in a relatively dry state and with but a relatively small amount of water remaining therein. It will further 105 be seen that the first set of press rolls acts upon the web while it is still in contact with the felt on one or both sides, while the second set of press rolls acts upon the pulp directly so that it is subjected to pressure between 110 the hard, smooth surfaces of the rolls instead of between felts.

The second set of press rolls 42, 43, is 115 rotated at a somewhat greater peripheral speed than is the first set of press rolls 17, 18. As a result, the pulp web is broken along the weakened portions thereof and separated into sheets, so that it is the separated sheets of the web which pass between the second set of press rolls and which are 120 there subjected to the further removal of water therebetween. These pulp sheets are still sufficiently wet so that they are slippery, but the corrugated surfaces of the press rolls 42 and 43 nevertheless grip the sheets and 125 draw them positively between the rolls without the aid of felts.

Power is applied to the machine in any suitable manner, such as by means of a pulley 49 mounted on shaft 50. Upon this

shaft is a pinion 51 which meshes with a gear 52 on the shaft of the lower press roll 18. This gear 52 also meshes with an intermediate gear 53 mounted on a shaft 54, and 5 the pinion 53 also meshes with a gear 55 on the shaft of the lower press roll 43. It will thus be noted that the lower press rolls 18 and 43 are directly connected so that they have a constant relative rotation. The gear 10 55 is somewhat smaller than the gear 52, while the press rolls 18 and 43 are of substantially the same size. The peripheral speed of the roll 43 is accordingly somewhat greater than that of the roll 18. The portion 15 of the web passing between the press rolls 42 and 43 is accordingly caused to move at a speed in excess of the speed of movement of the portion passing between the rolls 17 and 18. This difference in speed causes the 20 web to be broken or severed along the weakened transverse lines. The distance between the two sets of rolls, and the arrangement of the table 41, are preferably such that the breaking takes place near the upper end of 25 the table. The free end of the web will then slide down the table and will in turn be engaged by the corrugated surfaces of the second set of press rolls. The separated sheets, after passing between the second set 30 of press rolls, and being further dried by this operation, are collected in any suitable manner or further conveyed to the desired place of storage or shipment. They may thus be collected in a horizontal or inclined 35 box such as the box indicated at 56.

The two sets of press rolls 17, 18 and 42, 43, may have the rolls of each set geared together, preferably on the opposite ends of the rolls from those to which the main 40 driving gears are connected.

The modified construction illustrated in Fig. 4 corresponds to that portion of the machine illustrated in Fig. 2. That is, Figs. 1 and 4, taken together, show the complete 45 modified form of the machine. The construction illustrated in Fig. 4 is somewhat simpler and I regard it as more advantageous. The frame shown in Fig. 4 is made as a casting of sufficient strength, and it 50 has a straight upper surface which can be machined and which serves as the support for the other parts of the machine. This construction of the frame avoids the stepped construction of Fig. 2, and provides added 55 strength.

Certain of the parts of Fig. 4, which are similar to those of Fig. 2, are indicated by the same reference characters with suffixes appended thereto. Thus there are provided, in the construction of Fig. 4, two sets 60 of press rolls arranged and adapted to act upon the pulp successively. The first set of press rolls 17^a, 18^a, has the upper roll arranged with its center somewhat back of 65 the center of the lower roll, this arrange-

ment promoting the action of the rolls in removing water from the pulp. The lower roll 18^a is supported by suitable bearings carried by the lower frame. The upper roll 17^a is supported in bearings 72 which are 70 adjustably carried by the frame member 70, the end of this frame being secured to the lower frame member by the bar 71. Thus roll 17^a is forced downward by the spring 75 75 73, the tension of which can be increased or decreased by the screw member 74 having an operating handle 75. This arrangement provides for the direct action of the spring upon the upper roll, which is nevertheless yieldably held against the lower roll. A 80 cross beam or platform 76 enables the operator to gain access to the central portion of the machine. This beam or platform is 85 suitably supported by the end frame members. 85

The second set of press rolls 42^a 43^a, is similarly arranged with the upper roll offset, as shown, this arrangement materially promoting the desired dehydration of the pulp. The lower roll 43^a is supported by 90 suitable bearings carried by the upper frame members. The upper roll 42^a is held in bearings carried by the pivoted member 77 which is pivotally supported by the upright frame member 78. The opposite end 95 of the member 77 is held by the rod 79 and the compound levers 80, 81, 82. The rod 79 is adjustable by means of a nut screw-threaded upon its upper end and adapted to be operated by the wrench or operating handle 84, while the pressure applied to the roll can be increased or decreased by moving the weight 83 upon the lower lever 82. The rod 84^a and hand wheel 85 enable the roll 42^a to be raised, when this is desired. In 100 order to raise the roll, the weight 83 is removed or the pressure on the left-hand end of the member 77 is released, and the hand wheel 85 is then screwed down to the desired extent. 105

The felt which supports the pulp web passes between the first set of press rolls 17^a, 18^a, and thence over the idlers 19^a and 19^b, from which it returns around the idler 20^a in a manner similar to that above 110 described in connection with Fig. 2. After leaving the lower carrying felt, the pulp web passes to the second set of press rolls 42^a, 43^a. If the felt does not approach near enough to these rolls, a table 41^a can be 115 interposed for assisting in guiding the web from the felt to the press rolls. This table 41^a may be of varying width, or it may be omitted altogether where the arrangement of the felts is such as to discharge the web 120 directly between the press rolls. 125

The second set of press rolls, as previously described in connection with Fig. 2, is operated at a somewhat increased speed as compared with the first set of press 130

rolls, so that the pulp web is separated into sheets along the weakened transverse portions thereof. These separated sheets are then passed between the second set of press 5 rolls where they are further dehydrated, and the dehydrated sheets are then discharged from the machine.

The discharge mechanism shown in Fig. 4 is of an automatic character and is intended 10 to discharge the separated sheets with a minimum of manual labor into a suitable receptacle therefor. This discharge mechanism is made up of the two rolls 86 and 87, suitably supported, and having the two 15 felts 88 carried thereby. The roll 86 is supported in suitable bearings in the upright frame member 78, while the roll 87 is adjustably supported by members 89 and 91. The distance between these members 20 can be varied, and the roll 87 can be raised or lowered by means of the adjustable member 89 which has a slotted portion in which the bolt 90 operates. The roll 86 is driven by a crossed belt or chain from a pulley 25 or sprocket 53^b and which acts upon a similar pulley or sprocket 86^b. The size of the pulley or sprocket 86^b with respect to the pulley or sprocket 53^b is such that the belts 88 are speeded up and run much faster than 30 the pulp web passing through the machine. These belts pick up the separated sheets and discharge them at an increased velocity into a suitable receptacle 92 therefor. This receptacle may be conveniently arranged below the belts 88 so that the discharged sheets will fall into it by gravity, or by the combined action of gravity and of the impetus given to the sheets by the rapidly moving discharge belts 88.

From Fig. 5 it will be noted that the two belts 88 are separated a somewhat greater distance at their outer ends than at their inner ends. This is due to the construction of the rolls 86 and 87 with a slight taper to 45 ward or away from the center, as shown. This arrangement promotes the separation of the sheets from each other along the median line into which the pulp web is cut by a water jet (shown at 102, Fig. 1, and to be 50 described later) at the time of its formation. The two halves of the web sheets are therefore separately discharged at the same time by the two belts 88.

The two press rolls 42^a and 43^a are provided with doctors of improved construction. The lower doctor 97 is supported at 55 its ends by projections 96 carried by the upright frame members 78, such projections being provided with a slot, or the doctor itself 60 being provided with a slot which permits of adjustment of the doctor, and through which passes bolt 100 for securing the doctor in place. In order to strengthen the doctor longitudinally it has secured 65 thereto an angle iron member 98.

The upper doctor 94 is similarly adjustable upon and carried by a supporting and guide member or projection 93 being held in adjusted position by means of bolt 101 and it likewise has a stiffening angle iron 70 95 secured to its upper surface. The two doctors are adjustable toward and away from the rolls and can be held in adjusted position. They are of simple construction but nevertheless effective for their intended 75 purpose of preventing the sheets from following either of the press rolls and for guiding the sheets on to the delivery belts 88.

The preferred construction of the screen cylinder is illustrated in detail in Figs. 7, 8 80 and 9. As thus illustrated, the shaft 57 of the cylinder is provided with a plurality of spiders including two similar end spiders 58 and a number of intermediate spiders 59, all being secured to the shaft by means of set- 85 screws or other suitable fastening means. The spiders are secured together by a plurality of tie-rods 60.

Around the peripheries of the spiders 59 are a plurality of rods 61, preferably round, 90 and laid in grooves provided for their reception, as indicated in Figs. 8 and 9. The end spiders 58 are slightly larger in diameter than the intermediate spiders and are provided with openings in which the ends 95 of the rods 61 are secured. In addition to these rods 61, a number of rods 62 of relatively much larger cross-section are secured to the spiders at intervals around the circumference of the screen cylinder. Fig. 9 100 shows one of these rods 62, as substantially square in cross-section. In Fig. 1, five such rods 62 are shown, these being spaced apart at equal distances around the cylinder. Upon the rods 61 and 62 there is wound a 105 wire of suitable size, as illustrated in Fig. 7 and upon this wire are arranged the screen fabrics of appropriate mesh.

In the operation of the screen cylinder the pulp in the vat 7 is taken up upon the 110 surface of the cylinder in a relatively thin layer, which may be regulated in the manner above referred to. The layer of pulp overlying the relatively large rods 62, are thinner than the other portions of the web 115 because the pulp fibers do not build up so rapidly on these portions of the cylinder's surface. Accordingly, the continuous web formed upon the cylinder is weakened along 120 transverse lines corresponding with the positions of the rods 62. It will be evident that the size of the sheets will be determined by the distance apart of these rods, and that the size of the sheet can be regulated by varying the positions of these rods on the 125 cylinder. It will also be evident that the outer surface of the screen cylinder is continuous and free from obstruction and from any projections. That is, the weakened portions of the web are formed by positioning 130

the rods 62 within the effective screen fabric instead of by arranging projections outside the screen fabric.

The web is weakened longitudinally by 5 means of a water jet which plays at 102 against the pulp as it is carried on felt 9 around roll 11. The water is supplied through a main pipe 103, which lies transversely of the vat 7, and a branch pipe 104.

10 After the web has been formed upon the screen cylinder it is then passed between the various sets of rolls in the manner already described and the web is finally converted into sheets which are relatively dry 15 and which are adapted for shipment without further treatment. The construction and arrangement of the apparatus is such as to give pulp sheets of reduced moisture content as compared with similar sheets produced by the machines.

Where the second set of press rolls is corrugated in the manner illustrated and described, or in other appropriate manner, the pulp sheets will have upon their surfaces 25 slight projections corresponding to the grooves upon the corrugated rollers. The pulp sheets will thus have a pleasing and distinctive appearance.

Instead of forming a continuous web upon 30 the screen cylinder and passing this web through the machine, separate sheets may be formed which are substantially unconnected. It will be evident that the thickness of the web along the lines where it is weakened is 35 dependent upon the effective width of the bars 62. The width of these bars may be increased to such an extent that the fibers of the pulp will not build up thereon to any appreciable extent, in which case the web 40 will be formed of substantially separate sheets rather than as a continuous web, the length of the sheets being the circumferential distance between adjacent bars 62. In Fig. 8 bars 62^a are shown of a width adapted 45 for this purpose.

From the preceding description, taken together with the illustration, it will be seen that the present invention provides an improved machine of the character described 50 having two successive sets of rolls between which the sheet of pulp is passed, with successive removal therefrom of increased amounts of water. It will also be seen that the pulp, but not the felt, is passed between 55 the second set of rolls which are adapted to subject it to a greater pressure than the felt could safely stand without injury. While the second set of rolls is illustrated as a grooved set of rolls, it will be understood 60 that the rolls may be otherwise constructed to insure that the sheet or web of pulp will be positively drawn between the rolls and there subjected to compression and dehydration. It will also be seen that the sheet of 65 pulp is suitably guided and conveyed from

the first set of rolls to the second set, for example, by passing it over a horizontal or inclined table, which table, however, may be done away with if the web or layer is otherwise suitably guided and conveyed. So also, while the second set of rolls is shown as having the grooved portions thereof separated a distance less than the thickness of the sheet or web, this separation is not essential provided the rolls are so constructed as to insure the positive passage of the web therebetween, although the spacing apart of the grooved rolls is an advantageous construction.

I claim:

1. A pulp machine comprising means for forming a pulp web, a felt for carrying the web, a set of press rolls between which both the web and felt pass, and a second set of press rolls arranged beyond the first between which only the web passes, said sets of press rolls being constructed and arranged to subject the web to a heavy pressure to remove water therefrom.

2. A pulp machine comprising means for forming a pulp web with transverse weakened portions therein at intervals, a felt for carrying the web, a set of press rolls between which both the web and felt pass, and a second set of press rolls arranged beyond the first and arranged to be rotated at a greater peripheral speed than the first, said sets of press rolls being constructed and arranged to subject the web to a heavy pressure to remove water therefrom.

3. A pulp machine comprising means for forming a pulp web with transverse weakened portions therein at intervals, a felt for carrying the web, a set of press rolls between which both the web and felt pass, and a second set of corrugated press rolls arranged beyond the first and between which only the web passes, said second set of press rolls being arranged to be rotated at a greater peripheral speed than the first, and both sets of press rolls being constructed and arranged to subject the web to a heavy pressure to remove water therefrom.

4. A pulp machine comprising means for forming a pulp web with transverse weakened portions therein at intervals, a set of press rolls between which the web passes, and a second set of press rolls arranged beyond the first and arranged to be rotated at a greater peripheral speed than the first, said second set of press rolls having helical grooves therein to the ends and forming corrugations for assisting the passage of the web therebetween.

5. A pulp machine comprising a screen cylinder for forming a pulp web and means for subjecting the web so formed to pressure to remove water therefrom, said screen cylinder having a screen periphery and having relatively large bars within and adjacent to

the screen periphery and spaced apart to form weakened transverse portions in the web.

6. A pulp machine comprising means for forming a pulp web and means for subjecting the web so formed to pressure to remove water therefrom, said means including a set of corrugated press rolls having symmetrically disposed sets of helical grooves constructed and adapted to engage the pulp positively and draw it therebetween and to subject it to a heavy pressure to remove water therefrom.

7. A pulp machine having a set of press rolls which normally bear upon each other only at their ends and have their central portions spaced apart a distance less than the thickness of the pulp web to be subjected to pressure therebetween, whereby the central portions of the roll bear upon the pulp web while it is passing therebetween, but the rolls bear upon each other at their ends when no pulp web or sheet is passing therebetween.

8. A pulp machine having a set of press rolls having symmetrically disposed sets of helical grooves therein and forming corrugations for assisting the passage of the pulp web or sheet therebetween.

9. A pulp machine comprising means for forming a pulp web, a set of press rolls between which the web is passed and subjected to a heavy pressure, a second set of press rolls arranged beyond the first for subjecting the web to a heavy pressure, and a stationary table arranged between said sets of rolls for supporting the web in its passage from the first set to the second set.

10. A pulp machine comprising means for forming a pulp web, a felt for carrying the web, a set of press rolls between which both the web and felt pass and between which the web is subjected to a heavy pressure, a second set of press rolls arranged beyond the first and arranged to be rotated at a greater peripheral speed than the first and to subject the web to a heavy pressure, and a table interposed between the two sets of rolls for supporting the web and sheets separated therefrom during their passage from the first set of rolls to the second.

11. A pulp machine comprising means for forming a pulp web with transverse weakened portions therein at intervals, a set of press rolls between which the web is passed and subjected to a heavy pressure, a second set of press rolls arranged beyond the first for subjecting the web to a heavy pressure, said second set of press rolls being adapted to be rotated at a greater peripheral speed than the first, whereby the web is broken into

sheets along the weakened transverse portions, and delivery means for the sheets escaping from the second set of press rolls, said delivery means being arranged to receive the separate sheets of pulp and traveling at a sufficiently rapid rate to discharge the sheets into a receptacle therefor.

12. A pulp machine comprising means for forming a pulp web with transverse weakened portions therein at intervals, two sets of press rolls between which the web is successively passed and subjected to a heavy pressure to remove water therefrom, the second set of press rolls being rotated at a greater peripheral speed than the first whereby the web is broken into sheets along the weakened transverse portions, and delivery means arranged to receive the sheets from the second set of rolls and to discharge them into a receptacle therefor, said delivery means comprising one or more traveling belts adapted to travel at a materially increased speed as compared with the peripheral speed of the rolls, and being adjustable to discharge the sheets into a receptacle at different levels.

13. A pulp machine comprising means for forming a pulp web with transverse weakened portions therein at intervals and for cutting or dividing said web longitudinally into two parts, two sets of press rolls between which the two halves of the web are passed successively and subjected to a heavy pressure, the second set of press rolls being rotated at a greater peripheral speed than the first, whereby the two halves of the web are broken into sheets along the weakened transverse portions, and delivery means for delivering the separate sheets thus formed, said delivery means including two belts each adapted to receive and separately discharge the sheets from each half of the pulp web.

14. A pulp machine comprising means for forming a web with a longitudinal weakened portion therein, press rolls between which the web is passed and delivery means which exert a transverse pull upon the web and separate it along the longitudinal weakened portion.

15. A pulp machine comprising means for forming a web with a longitudinal weakened portion therein, press rolls between which the web is passed and delivery means which exert a transverse pull upon the web and separate it along the longitudinal weakened portion, said delivery means comprising two diverging belts.

In testimony whereof I affix my signature.
HARRY E. TIDMARSH.
